UNITED STATES PATENT OFFICE

157,304

VANITY DRESSER

Howard A. Thede, Wayland, Mich.

Application September 13, 1948, Serial No. 148,569

Term of patent 3½ years

(Cl. D33—6)

To all whom it may concern:

Be it known that I, Howard A. Thede, a citizen of the United States, residing at Wayland, in the county of Allegan and State of Michigan, have invented a new, original, and ornamental Design for a Vanity Dresser, of which the following is a specification, reference being had to the accompanying drawing, forming part thereof.

I claim:

The ornamental design for a vanity dresser, substantially as shown.

HOWARD A. THEDE.
